UNITED STATES PATENT OFFICE.

HERBERT J. BARNES, OF READING, PENNSYLVANIA.

HEADLIGHT.

1,287,611.

Specification of Letters Patent. Patented Dec. 17, 1918.

Application filed September 6, 1917. Serial No. 139,962.

To all whom it may concern:

Be it known that I, HERBERT J. BARNES, a citizen of the United States, residing at Reading, in the county of Berks and State 5 of Pennsylvania, have invented certain new and useful Improvements in Headlights, of which the following is a specification.

My invention relates particularly to road vehicle head lights having means for avoiding the ordinary blinding effect thereof, and it consists in the improved construction hereinafter fully described in connection with the accompanying drawing and the novel features of which are clearly defined 15 in the subjoined claims.

Figure 1 is a longitudinal vertical section illustrating the general form and arrangement of my improved headlight.

Fig. 2 is a front view thereof. 20 Fig. 3 is a cross-sectional view on the line 3—3 of Fig. 1.

The upper portion of my improved headlight, as shown, is of ordinary form, comprising the usual parabolic reflector 5, with 25 vertical circular window 6, and focal light 7; the projecting wiring 8 for the latter being inclosed as heretofore by an outer casing 9.

In my improved construction a supplemental reflector section 10 is provided, extending partly around the parabolic reflector 5; the convexly curved exterior wall 15 of such inclosed portion of the latter being shown as forming the upper reflecting wall of said 30 supplemental section, and a concavely curved reflector wall 16 forming the lower reflector thereof. As shown in Figs. 2 and 3 the supplemental reflector section 10 thus formed is of substantially crescent-shaped 35 cross-section; the cross-sections reducing in area rearwardly to the intersection 17 of the reflector walls 15 and 16. A separate light 18, located forward of this intersection, is provided in the supplemental section 10; the 40 connected wiring being inclosed, as shown, by a continuation 9^a of the inclosing casing 9 of the parabolic reflector section, and suitable switches being provided for independently or jointly controlling the separate 45 lights. The window 20 of the supplemental reflector section 10 is crescent shaped to correspond with the cross-sectional form of 50 said section, and is inclined rearwardly from

the plane of the circular window 6, as shown, against the receding edge of the 55 lower reflector 16.

The supplemental reflector 10 is primarily intended to be thrown into service when the main reflector 5 is thrown out to avoid the blinding effect incident to the latter; though 60 they may be used together when desired, either with the main light in reflector 5 or with a dimmer light as heretofore provided. The form and arrangement of the supplemental reflector 10 is adapted to reflect its 65 rays of light into substantially horizontal or downward lines, so as to most satisfactorily illuminate the whole road and the adjacent side while avoiding any glare objectionable to an approaching driver. The described use of a portion of the exterior surface of the reflector 5 as the top wall of the supplemental reflector 10 is simple and advantageous, but a separate wall plate for such use may obviously be employed if desired, and the shown construction otherwise modified within the spirit of the invention. 70

What I claim is:

1. In a headlight, a supplemental substantially semi-parabolic reflector, a focal lamp arranged within the axis of the reflector, a main parabolic reflector having a considerable portion below its axis overhanging the axis of the lamp in the supplemental reflector and a focal lamp in the main reflector, the axes of said lamps being parallel. 80

2. A headlight comprising a supplemental substantially semi-parabolic reflecting section having a focal lamp arranged in the axis thereof, a main parabolic reflector having its outer surface provided to produce a reflecting surface for the lamp in the supplemental reflecting section and a focal lamp in the main parabolic reflector, said main parabolic reflector having a considerable 85 portion of its outer reflecting surface overhanging the axis of the lamp in the supplemental reflecting section. 90

3. In a headlight, a supplemental substantially semi-parabolic reflecting section, a lamp arranged within the axis of the section, a main parabolic reflector having a considerable portion arranged to one side of its axis overhanging the axis of the lamp in the supplemental section and a focal lamp 95 in the main reflector, the axes of the lamps 100 in

and of the reflectors being parallel and the axis of the lamp first named intersecting the wall of the main reflector at a point spaced inwardly from the periphery thereof.

5. 4. In a headlight, a main parabolic reflector having a horizontal axis, a supplemental parabolic reflecting section having an axis parallel to the axis of the main reflector, lamps in said reflectors, the outer

surface of the main parabolic reflector producing a reflecting surface which directs certain rays in the supplemental reflector contrary to the axis of said reflector, and a lens for the supplemental reflector section positioned normal to said rays.

In testimony whereof I affix my signature.

HERBERT J. BARNES.
